The ornamental design for a probing head for an electrical test probe, as shown and described.

DESCRIPTION

FIG. 1 is a top, front, and left side perspective view of the probing head for an electrical test probe showing my new design;

FIG. 2 is a left side elevation view having a mirrored right side elevation view of the probing head for an electrical test probe showing my new design;

FIG. 3 is a top plan view thereof;

FIG. 4 is a bottom plan view thereof;

FIG. 5 is a front elevation view thereof; and,

FIG. 6 is a rear elevation view thereof.

FIG. 1

FIG. 3

FIG. 2

FIG. 4

FIG. 6
